DESCRIPTION

U.S. PATENT DOCUMENTS

FIG. 1 is a front, top perspective view of a fascia tissue treatment device with a matrix of nine treatment elements; FIG. 2 is a front elevational view of the device of FIG. 1; FIG. 3 is a rear elevational view of the device of FIG. 1; FIG. 4 is a right-side elevational view of the device of FIG. 1; FIG. 5 is a left-side elevational view of the device of FIG. 1; FIG. 6 is a top view of the device of FIG. 1; and, FIG. 7 is a bottom view of the device of FIG. 1. The broken lines shown as dashed lines are for the purpose of illustrating unclaimed structure, and form no part of the claimed design.
